UNITED STATES PATENT OFFICE

ALBERT PFLUEGER, OF MIAMI, FLORIDA

MEANS FOR MOUNTING THE SKINS OF FISH

Application filed February 12, 1932. Serial No. 592,610.

This invention relates to ichthyological taxidermy, and in accordance with the present invention improved means for mounting the skin of fish is provided.

5 The present invention is an improvement over the means for mounting the skin of fishes forming the subject matter of my co-pending application Serial No. 583,965 and filed under date of December 30, 1931.

10 The present invention together with its many objects and advantages will be best understood from a study of the following description, taken in connection with the accompanying drawings wherein:

15 Figure 1 is a side elevational view of the fish skin prepared and mounted in accordance with my invention.

Figure 2 is a side elevational view of a solid filling, ready for disposition within the skin 20 of the fish.

Figure 3 is a fragmentary longitudinal sectional view through the solid filling.

Figure 4 is a transverse sectional view 25 through the fish shown in Figure 1.

Figure 5 is a perspective view of the core or body of the solid filling prior to the shaping of said core.

Figure 6 is a side elevational view of the core subsequent to the shaping thereof.

30 Figure 7 is a transverse sectional view through the core shown in Figure 5.

Figure 8 is a transverse sectional view through the core as shown in Figure 6.

35 Referring more in detail to the drawings, it will be seen that 10 designates generally a core or solid filling, and in the present instance the core 10 is formed from a plurality of plies, including an intermediate ply or strip 11 curved longitudinally and of any suitable material. Applied to the convex and concave side respectively of the intermediate strip 11 is a pair of relatively narrow strips 12, each strip 12 being of a width equal to 40 one half the width of the strip 11. Strips 11 and 12 are preferably formed of wood and strips 12 are secured to the strip 11 through the medium of pegs or other suitable fastening elements 13.

45 Subsequent to the assembling and securing together of the strips 11 and 12, the core

formed thereby is shaped so as to correspond in outline to the body 14 of the fish (see Figures 3, 4 and 8) exclusive of the fins, tail and other such parts of the fish body. The outline of the core 10 may be formed in any suitable manner as will readily present itself to those skilled in the art. In this connection, it will be noted that the head or largest end of the core 10 is notched as at 15 to provide for the mouth of the fish.

50 When the outline of the core 10 has been formed the exterior surface of the core is wholly covered with a coating 16 of papier-mâché or similar substance such as plaster, putty, etc.

55 The solid filling consisting of the core 10 and the coating 16 is then placed in the skin 14 of the fish after which the skin is smoothed over, and the skin with the solid filling may now be placed on a board for drying purposes and the outer surface of the skin treated in any usual manner.

60 Even though I have herein shown and described the preferred embodiment of the invention, it is to be understood that I do not wish to limit myself to the particular details of construction, combination and arrangement of elements herein shown and described or materials used, and accordingly claim all 65 such forms of the invention to which I am entitled by the requirements of the prior art and the scope of the appended claim.

68 Having thus described my invention, what I claim as new is:

70 A core for the mounting of a skin of a fish comprising a central strip of wood and a number of strips of wood attached to each face of the central strip, said strips being slightly bowed longitudinally to form a concavity at one side of the core with its other side convex and said core being shaped to fit in the skin and having a notch in its head end for the mouth of the specimen, and a coating 75 of plastic material entirely enclosing the core.

80 ALBERT PFLUEGER.
